UNITED STATES PATENT OFFICE.

ROBERT P. CARR, OF BUFFALO, NEW YORK, ASSIGNOR TO U. S. HAME COMPANY, OF BUFFALO, NEW YORK, A CORPORATION OF NEW YORK.

METHOD OF MAKING HAMES.

1,132,513.

Specification of Letters Patent.

Patented Mar. 16, 1915.

Application filed October 16, 1914. Serial No. 866,904.

To all whom it may concern:

Be it known that I, ROBERT P. CARR, a citizen of the United States, and resident of Buffalo, in the county of Erie, in the State of New York, have invented new and useful Improvements in Methods of Making Hames, of which the following, taken in connection with the accompanying drawings, is a full, clear, and exact description.

This invention has reference more particularly to the method of manufacturing sheet metal hames of the type in which the hame is formed from a single piece or blank of sheet metal, and the object of this invention is to improve, simplify and cheapen the process of manufacture and construction of hames of this type, and produce a neat appearing, strong and durable hame which will resemble a wooden hame in size, weight and general appearance, but will be much stronger and more durable.

Other objects and advantages will appear from the following description taken in connection with the accompanying drawings, in which—

Figure 1 is a view of a sheet metal plate from which a pair of hame blanks can be cut economically. Fig. 2 is a view of a metal hame blank as cut from the metal plate. Fig. 3 illustrates the next step in the process, consisting in stamping a series of perforations or holes near the opposite edges of the plate for the reception of attaching means for the usual wear leather. Fig. 4 illustrates the next step in the process, consisting in off-setting a section of the plate to form a step-portion extending longitudinally of the blank. Fig. 5 illustrates the next step in the process, consisting in pressing the blank into trough or U-shape form. Fig. 6 is a cross section on line 6—6, Fig. 4. Fig. 7 is a cross section on line 7—7, Fig. 5. Fig. 8 represents a permanent core for the hame, showing the preferred position of the kerfs. Fig. 9 illustrates the next step in the process, consisting in bending the edges of the opposite ends of the sheet metal blank around the permanent core. Fig. 10 illustrates the next step in the process, consisting in completing the bending of the blank to entirely inclose the core. Fig. 11 is a cross section on line 11—11, Fig. 9. Fig. 12 is a cross section on line 12—12, Fig. 10. Fig. 13 illustrates the next step in the proc-

ess, consisting in bending the hame longitudinally, its opposite ends being bent in opposite directions. Fig. 14 illustrates the next step in the process, comprising the formation of an opening or conduit through the reinforced end of the hame for the reception of a hame strap attaching member. Fig. 15 illustrates the next step in the process, the punching of a series of openings in one side of the hame for the reception of attaching means for the trimmings and draft devices of the hame. Fig. 16 is a longitudinal section on line 16—16, Fig. 15. Fig. 17 illustrates the next step in the process, comprising the punching of openings in the opposite side of the hame registering with openings punched in the other side for the passage of the attaching means mentioned. Fig. 18 is a longitudinal section on line 18—18, Fig. 17. Fig. 19 is a view of the finished hame.

Each step of the process herein is illustrated in the accompanying drawings, and can best be described with reference thereto.

—1— represents a flat piece of sheet metal from which a pair of similarly shaped blanks —2— may be cut as shown in dotted lines upon the Fig. 1. The blank —2— is of the form shown in Fig. 2 and is provided at one end with a lateral edge extension or ear —3—. The blank —2— has a suitable series of openings —4— punched adjacent the opposite edges thereof for the reception of tacks or similar attaching means for a wear leather —5—. A longitudinal section of the blank —2— is then offset from the remainder of the blank by suitable pressure, or otherwise, to form a step-portion —6— longitudinally of the blank, as shown in Figs. 4 and 6. The blank is then bent into trough or U-shape, of the form illustrated in Figs. 5 and 7. This U-shaped blank is then adapted to receive a permanent core —7— of wood or other suitable material, such core being illustrated in Fig. 8, and having a series of slots or kerfs —8— formed therein, so that the core may be bent with the sheet metal shell to the desired form in the finished hame. The core —7— is placed in the trough-shaped blank and the opposite edges of the ends of the blank are bent, as by suitable dies, around the core, the lateral edge extension —3— overlapping the opposite edge of the

blank to reinforce the same for a purpose hereinafter described, as shown in Fig. 9. The intermediate portions of the opposite edges of the blank and are bent down to entirely inclose the core, as shown in Figs. 5 10, 11 and 12, and abut in a joint extending longitudinally of the hame and preferably positioned on the flat back. The sheet metal blank with its permanent core now 10 has the form in cross section of the completed hame, but is substantially straight throughout its length. The next step in the process consists in bending the blank and its core longitudinally to the shape of a completed hame, the opposite ends of the hame being bent or deflected in opposite directions, as shown in Fig. 13. A suitable conduit or opening 9' is then drilled through the end of the hame at which the lateral edge 15 extension —3— is positioned for the reception of a bolt or other suitable device —9— for securing a hame strap attaching member —10— to the hame and this opening extends through the sheet metal shell, the permanent core and the lateral edge extension —3—, the extension —3— forming an additional thickness of metal for supporting such attaching means, as shown in Fig. 14. The next step in the process consists in 20 punching a suitable series of openings —11— through the sheet metal along one side of the hame, as shown in Fig. 16. A suitable series of openings —12— are next punched in the opposite side of the hame, 25 said openings registering with openings —11— punched in the opposite side of the hame for the passage of staples, bolts or other suitable means for attaching the trimmings and draft devices of the hame. These 30 staples, when passed through these openings in one side of the sheet metal hame and driven or otherwise forced through the wooden core, preferably are of sufficient length to extend a short distance from the 35 opposite side of the hame in such manner as to be offset or clenched against the sheet metal wall.

The trimmings and draft devices, as shown in Fig. 19, comprise the ball cap —13— as 40 shown formed with a flange —14— extending longitudinally of and attached to the hame, the top loop staple —15— with its loop ring —16—, the line ring —17—, the back-strap ring —18—, and the hame strap attaching member —10—. The back-strap ring —18— and the line ring —17— are 45 preferably attached to the hame by members extending through the sheet metal shell at opposite sides of the longitudinal joint, and offset or clenched against the face thereof to not only firmly support the said rings, but to strengthen the shell and prevent any tendency to spread at the joint. A supplementary ring —19— may likewise be attached to the hame in a similar manner.

The overlapping edge extension —3— not only serves to reinforce this end of the hame, but the bolt —9— passing therethrough and through the metal shell also tends to prevent any movement of the opposite edges of the 70 blank from their abutting position.

The completed hame is similar in many respects to that shown in Letters Patent No. 1,091,874 and No. 1,098,928, granted to C. L. Wiedrich, March 31, 1914 and June 2, 1914, 75 respectively, and although I have shown and described this particular form of hame as constructed in accordance with the method herein, yet it is readily apparent that this series and sequence of steps and operations 80 may be applied to the manufacture of sheet metal hames of various forms, shapes and constructions, without departing from the spirit of the invention as set forth in the appended claims.

What I claim is:

1. The method of making hames, consisting in forming a sheet metal blank of desired shape, punching a series of openings in opposite edges thereof, offsetting a portion of said blank, bending the blank into trough shaped form, inserting in the trough shaped blank a permanent core suitably kerfed, bending the opposite edges of the ends only of the blank around the core, then bending 90 the intermediate portion of the blank around the core so that the edges abut in a joint extending longitudinally of the hame, then bending the blank and its core longitudinally, perforating the blank to receive attaching means for draft devices and trimmings, and securing the draft devices and trimmings in place.

2. The method of making hames, consisting in forming a suitable sheet metal blank, 105 bending the blank into trough shaped form, inserting into the trough shaped blank a permanent core, bending the opposite edges of the ends only of the blank around the core, then bending the intermediate portion of the blank around the core so that the edges abut in a joint, then bending the blank and its core longitudinally, perforating the blank to receive attaching means for draft devices and trimmings, and securing the 110 draft devices and trimmings in place.

3. The method of making hames consisting in forming a sheet metal blank of desired shape and having a lateral edge extension, punching a series of openings in the intermediate portion of the opposite edges of the blank, bending the blank into trough shaped form, inserting in the trough shaped blank a permanent core, bending the opposite edges of the ends only of the blank around the core so that the lateral edge extension overlaps the opposite edge of the blank, then bending the intermediate portion of the blank around the core so that the edges abut in a joint extending longitudi- 125 130

nally of the hame, forming an opening extending through the shell at opposite sides of the joint and through the lateral edge extension for the reception of attaching means for a hame strap, then bending the blank and its core longitudinally, perforating the opposite sides of the blank to receive attaching means for draft devices and

trimmings, and securing the draft devices and trimmings in place.

In witness whereof I have hereunto set my hand this ninth day of October, 1914.

ROBERT P. CARR.
